[57] **CLAIM**

The ornamental design for a panel assembly for bowling lanes, as shown and described.

DESCRIPTION

FIG. 1 is a perspective view taken from the front, above and to the right of a panel assembly for bowling lanes of the invention;

FIG. 2 is a front view of the panel assembly for bowling lanes of FIG. 1;

FIG. 3 is a left side view of the panel assembly for bowling lanes of FIG. 1;

FIG. 4 is a right side view of the panel assembly for bowling lanes of FIG. 1;

FIG. 5 is a back view of the panel assembly for bowling lanes of FIG. 1; and,

FIG. 6 is a top view of the panel assembly for bowling lanes of FIG. 1.

The broken lines showing vertical supports are for illustrative purposes only, and form no part of the claimed design.

FIG. 1

FIG. 2

FIG. 3

FIG. 4

FIG. 5

FIG. 6
